UNITED STATES PATENT OFFICE.

MATTHEW T. CHAPMAN AND MARK C. CHAPMAN, OF AURORA, ILLINOIS, ASSIGNORS
TO AMERICAN WELL WORKS, OF AURORA, ILLINOIS, A CORPORATION OF ILLINOIS.

PUMP.

1,167,886.

Specification of Letters Patent.

Patented Jan. 11, 1916.

Application filed October 26, 1910, Serial No. 589,216. Renewed December 9, 1915. Serial No. 66,021.

To all whom it may concern:

Be it known that we, MATTHEW T. CHAPMAN and MARK C. CHAPMAN, citizens of the United States, residing at Aurora, in the county of Kane and State of Illinois, have invented certain new and useful Improvements in Pumps, of which the following is a specification, reference being had to the accompanying drawings.

10 Our invention relates to deep-well pumps, and comprises certain improvements in pumps of the character shown and described in Letters Patent to Robert E. L. Holmes, No. 990,359, dated April 25, 1911, and the 15 application of Matthew T. Chapman, Serial No. 426,556, filed April 11, 1908.

The objects of our invention are to provide certain improvements by which the danger of splitting the pump cylinder by 20 the pressure of the water or an accidental blow from the pump rods, or any weight that may be let down suddenly, may be avoided; to increase the capacity of the pump without increasing the diameter of the 25 well-tube; to provide a construction by which the removal of the pump cylinder from the well-tube is facilitated; and to cheapen the cost of pumps of this character. We accomplish these objects as illustrated in 30 the drawings and as hereinafter described.

What we regard as new is set forth in the claims.

In the accompanying drawings,—Figure 1 is a vertical section of a part of a well-tube 35 showing the pump cylinder, the foundation which supports the same, the lower check valve, and also part of the pump-rod; Fig. 2 is a vertical section of the pump cylinder showing the piston, check valves, and pump-rod; Fig. 3 is an enlarged elevation of the 40 foundation which supports the pump cylinder; and Fig. 4 is a cross-section on line 4—4 of Fig. 1.

Referring to the drawings,—5 indicates 45 the well-tube, which forms the lining of the well and conducts the water from the pump cylinder to the outlet.

6 indicates the pump cylinder, which is a cylinder preferably of brass and is of some- 50 what greater length than the stroke of the piston. The pump cylinder is adapted to be fitted in the well-tube, being of an external

diameter slightly less than the internal diameter of the well-tube, as shown in Fig. 1. It is tapered at its lower end so as to fit into 55 and expand a cylindrical packing 7, which is preferably made of rubber, its upper end portion fitting between the tapered lower end of the pump cylinder and the well-tube, as shown in Fig. 1. 60

8 indicates a tube, preferably of brass, which is conical at its upper end, as shown at 9 in Fig. 1, and is provided with a series of longitudinal slots 10 at its lower end portion, as shown. The conical upper portion 65 9 of the tube 8 is adapted to receive the lower end portion of the packing 7, which fits snugly therein and is wedged tightly between the lower end of the pump cylinder and the upper end portion of the tube 8, 70 into which the pump cylinder projects, as shown. Thus a tight joint is made not only between the pump cylinder and the tube 8, but also between said parts and the well-tube. The tube 8, which forms a part of 75 the foundation which supports the pump cylinder, is secured in position by means of wedges 11 which fit between the funnel-shaped portion 9 of said tube and the well-tube and are themselves carried by a collar 80 12 having at its upper margin an internally-projecting flange 13. The wedges 11 are provided at their lower ends with flanges 14 which interlock with the flange 13, as best shown in Fig. 1. 85

15 indicates screws which are carried by the collar 12 and project inwardly a short distance through the slots 10, but terminate short of the center of the tube 8 so as to leave a free central passage therethrough. 90

Obviously, when the collar 12 is fitted upon the tube 8, the wedges 11 are held in position thereon, but by removing said collar from said tube the wedges may be readily removed. 95

16 indicates a collar screwed upon the lower end of the tube 8, and 17 indicates a spring between the collars 12 and 16 for normally holding said collar, with the wedges carried thereby, up in operative position. 100

The construction of the collar 12 and the wedges and the spring-support therefor, as shown herein, is similar to the construction

shown in Letters Patent No. 677,438, granted to us July 2, 1901, but differs therefrom in that in our present construction we provide a free passage through the tube 8 for the passage of the pump-rod or for the passage of tools; whereas in the construction shown in our said patent such open passage is not provided.

18 indicates a tubular pump-rod, which 10 extends down through the well-tube and pump cylinder. The pump-rod 18 is provided at a point above the pump cylinder with a check-valve 20, as shown in Fig. 2.

21 indicates the piston, which is carried 15 by the pump-rod and works in the pump cylinder 6, as shown in Fig. 2. The construction of said piston is best shown and described in the Holmes patent hereinbefore referred to and need not therefore be described again here, as it will suffice to say that the upper portion 18^a of the pump-rod connects with the lower portion 6^b of the pump cylinder through passages 22 in the piston, and that the lower portion 18^b of the 25 pump-rod connects with the upper portion 6^a of the pump cylinder by passages extending through the piston and normally closed at their upper end by a check-valve 23 spring-pressed upon its seat by a spring 30 24,—the arrangement being such that when the piston moves down the water flows up through passages 22 into the upper portion 18^a of the pump-rod, thence passing out into the well-tube through check-valve 20. At 35 the same time water rises through the lower portion 18^b of the piston-rod and the passages in the piston 21 and is discharged into the upper portion 6^a of the pump cylinder after passing under check-valve 23.

40 25—26 indicate lower and upper check-valves fitted, respectively, in the lower and upper end portions of the pump cylinder, as shown in Fig. 2. The lower check-valve 25 is seated upon a shoulder 27 provided in 45 the lower portion of the pump cylinder, being provided at its lower portion with a tapered disk 28, preferably of brass, which fits snugly upon said seat.

29 indicates packing disks or cups for 50 preventing leakage around the check-valve 25.

30 indicates a vertically-movable disk, which is seated at the upper portion of the 55 check-valve 25 and is spring-pressed upon its seat so as to prevent the downward flow of water from the lower portion 6^b of the pump cylinder.

60 The upper check-valve 26 is similar in many respects to the lower check-valve 25, but differs therefrom in that it is provided with a shoulder or radial flange 31 which is of greater diameter than the balance of the check-valve and rests upon the upper end of the pump cylinder, as shown in Fig. 2.

65 32 indicates a spring-pressed disk which

prevents downward flow of water through the valve 26.

It will be apparent from the foregoing that when the upper check-valve is in position, the upper end of the pump cylinder will be closed against the admission of debris, sand or other matter, but that the upward flow of water from the pump cylinder will not be interfered with. When the piston 21 is lifted water will be drawn upward through the lower check-valve into the lower portion 6^b of the pump cylinder and also will be lifted from the upper portion 6^a of the pump cylinder through check-valve 26 into the well-tube. Consequently, when the piston 21 is reciprocated, water will be lifted on both the upward and downward strokes, thereby giving a continuous flow of water in the well.

By the construction described, we make it 85 unnecessary to extend the pump cylinder to the top of the well, as has heretofore been the usual practice, thereby making a large saving in the cost of installation. We also make it possible to employ a much larger 90 pump cylinder in proportion to the size of the well-tube. This will be apparent when it is considered that where the pump cylinder extends to the top of the well it is impracticable to use a cylinder of more than 95 six inches in external diameter in an eight-inch well-tube, thus making the internal diameter of the cylinder only five and three-quarters inches; whereas with our present construction we can use a pump cylinder 100 having seven and one-half inches external diameter in an eight-inch well-tube—thereby nearly doubling the capacity of the well.

When it is desired to remove the pump cylinder, the pump-rod is drawn out, carrying with it the check valves 25—26 and piston 21; then, if the pump cylinder has not become tightly wedged in place by sand, gravel or other matter packing between it and the well-tube, it may be removed by inserting a tool which will engage its lower end and lift it out of the well. If, however, it has become tightly cemented in place, it may be removed by slitting it longitudinally or cutting out a longitudinal chip, 115 thereby permitting it to collapse. The foundation which supports the pump cylinder may also be removed by inserting an expanding tool which will engage its lower end and lift it, thereby releasing the wedges 120 11 from the wedging effect of the funnel-shaped portion 9 and permitting them to disengage the well-tube. The foundation is inserted in the well by means of a tool which engages the inwardly-projecting ends of the screws 15 and presses down upon them, thereby leaving the wedges free to move down into the well-tube at the desired point.

If desired, the upper portion of the pump cylinder may be provided with a shoulder 130

33 to further support the check-valve 26, as shown in Fig. 1, but ordinarily that is unnecessary.

That which we claim as our invention, and desire to secure by Letters Patent, is,—

1. In combination, a well-tube, a pump-cylinder therein, and means supporting said cylinder at any desired point along said well-tube, comprising a collar, wedge-members secured to said collar and spaced circumferentially of the collar in the well-tube, yielding means tending to hold said collar in operative raised position for causing the wedges to grip the well-tube for supporting the cylinder, and three or more pins extending inward from said collar adapted to be engaged from the interior of the cylinder for forcing said collar evenly up or down relative to said well-tube but adapted to permit the passage of a water-supply pipe through said collar.

2. In combination, a well tube, a pump cylinder therein, means for supporting said cylinder in said well tube, and a pump-rod extending through said cylinder and below said supporting means, said supporting means comprising a tube flared at its upper end portion, a wedge between said flared portion and the well tube, a spring mounted on said tube tending to hold said wedge in operative wedging position, and means connected with said wedge and extending into said tube close to said pump-rod adapted to be engaged from above for loosening said wedge in said well tube.

3. In combination, a well tube, a pump cylinder therein, means for supporting said cylinder in said well tube, and a pump-rod extending through said cylinder and below said supporting means, said supporting means comprising a tube flared at its upper end portion, a wedge between said flared portion and the well tube, a spring mounted on said tube tending to hold said wedge in operative wedging position, and a plurality of screws connected with said wedge and extending through longitudinal slots in the wall of said flared tube adapted to be engaged from above for loosening said wedge in said well tube.

4. In a pump, the combination with a well-tube, of a pump cylinder supporting device comprising a tube flared at its upper end portion, wedges between said flared portion and the well-tube, and means connecting said wedges with said supporting device and projecting slightly beyond the inner surface thereof, said supporting device having a free open passage adapted to receive a pump-rod.

5. In a pump, the combination with a well-tube, of a pump cylinder supporting device comprising a tube having its upper end portion flared and having longitudinal slots in its lower portion, a collar mount-

ed on said supporting device and having pins projecting through said slots beyond the inner surface of the tube, the inner ends of said pins being a distance apart sufficient to permit the passage of a pump rod between them, and wedges connected with said collar and adapted to engage the well-tube.

6. In a pump, the combination with a well-tube, of a pump cylinder tapered at its lower end, an internally and externally tapered support for said pump cylinder into which the lower end of said cylinder projects, and packing between the inner surface of the support and the pump cylinder, said support comprising a wedge adapted to grip the well-tube, yielding means tending to hold said wedge in gripping engagement with the well-tube, and means carried by said wedge adapted to be actuated from the interior of the well-tube for loosening the support from engagement with the well-tube.

7. In combination, a well-tube, a tapering tube therein, a collar about said tapering tube, wedge-members secured to said collar and spaced circumferentially of the collar in the well-tube, yielding means tending to hold said collar in operative raised position for causing the wedges to grip the well-tube for supporting the tapering tube, three or more pins extending inward from said collar adapted to be engaged for forcing said collar evenly up or down relative to said well-tube but adapted to permit the passage of a water-supply pipe through said collar, a tapering packing mounted in the well-tube and extending into the upper end of said tapering tube, and a cylinder having a tapered lower end extending into said packing and supported thereby upon the tapering tube, said packing serving to make a tight joint between the lower end of said cylinder and said well-tube.

8. A pump cylinder supporting device comprising a tube having wedges mounted thereon, a spring on said tube and acting to move said wedges upward, said tube having an internally-tapered portion for receiving a packing and having a free central passage, in combination with a cylinder having a tapered lower end fitting in said internally-tapered portion of the supporting device and packing between the lower end of the cylinder and the upper end portion of said tube.

9. The combination of a well-tube having a cylinder secured therein and a check-valve at the lower end portion of said cylinder, of a support for the cylinder adapted to be placed in said well-tube at any desired depth, a spring-actuated wedge for securing said support in position in said well-tube, and means extending inward from said wedge through the wall of the support adapted to be engaged for releasing the sup-

port from the well-tube, said releasing means leaving a free open passage for the passage of a pipe connected with the piston of a pump, and a pump piston operating in said cylinder and having a pipe extending through said support.

10. In a double-acting pump, the combination of a well-tube, a pump cylinder fitted therein, a support secured in the well-tube below and supporting said cylinder, said support being secured in the well-tube by means of wedge-mechanism adapted to be tightened into operative engagement with the well-tube, a check-valve in the lower

portion of said cylinder, a piston operating in said cylinder, a tube connected with said piston and extending down through said check-valve and said support, means extending into said support into close proximity to said tube adapted to be engaged on the inside of the support for loosening it from the well-tube, and a check-valve above said piston.
